UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,887, dated November 14, 1893.

Application filed October 7, 1893. Serial No. 487,508. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of ornamental scrolls formed of flowers and leaves arranged in the 10 form of open panels with a vase in the center filled with flowers and leaves as shown in the accompanying drawing.

In the border or upper portion of the design the ornamental scrolls are arranged in a horizontal direction and the vase ornaments filled 15 with flowers and leaves spring from the ornamental scrolls as shown in the drawing.

What I claim is—

1. The design for wall paper herein shown and described.
2. In the design for wall paper the border herein shown and described.

Witness my hand this 2d day of October, 1893.

CHARLES BOOZE.
